No. 746,524.

Patented December 8, 1903.

UNITED STATES PATENT OFFICE.

HELEN M. KISSLING, OF ORIOLE, INDIANA.

FAN.

SPECIFICATION forming part of Letters Patent No. 746,524, dated December 8, 1903.

Application filed June 20, 1903. Serial No. 162,444. (No model.)

To all whom it may concern:

Be it known that I, HELEN M. KISSLING, a citizen of the United States, residing at Oriole, in the county of Perry and State of Indiana, 5 have invented new and useful Improvements in Fans, of which the following is a specification.

This invention relates to fans; and the object of the same is to provide a simple and 10 effective construction whereby a greater amount of air will be impelled toward the user without requiring unusual exertion.

The invention consists in the construction and arrangement of the several parts, which 15 will be more fully hereinafter described and claimed.

The drawing shows a perspective view of a fan embodying the features of the invention.

The numeral 1 designates the frame or body 20 of the fan, which may be of any shape other than that shown and has a central rectangular opening 2 and an integral depending handle 3, by means of which the fan as an entirety may be oscillated. Within the opening 25 2 and mounted to freely rotate is a wing or beater 4, made of a shape corresponding to and of materially less dimensions than the opening 2 to permit unretarded rocking or oscillating movement of the said wing or 30 beater. The wing or beater 4 is movably held within the frame or body 1 by pivot-pins 5, secured to the side walls of said frame or

body and centrally engaging the wing or beater at opposite points.

In operation the fan is oscillated and the 35 wing or beater will be simultaneously oscillated, and a greater quantity of air will thus be impelled toward the user without undue exertion.

It is proposed to construct the fan of any 40 suitable material and also to ornament the parts thereof, as may be desired.

It is obvious that changes in the proportions and dimensions may be resorted to without departing from the spirit of the invention. 45

Having thus fully described my invention, what I claim as new, and desire to secure by Letters Patent, is—

A fan comprising a frame having a central rectangular opening therein, and an integral 50 handle, a flat wing or beater made of a shape corresponding to the opening and pivoted centrally therein and between its ends to the side bars of said frame so as to have a rocking or oscillating movement between the surrounding walls of said opening, substantially 55 as specified.

In testimony whereof I affix my signature in presence of two witnesses.

HELEN M. KISSLING.
